(57) **CLAIM**

The ornamental design for male body of connector for fluid tubing, as shown and described.

DESCRIPTION

This application is related to U.S. patent application Ser. No. 29/353,314 and Ser. No. 29/353,318 filed Jan. 6, 2010 pending.

FIG. 1 is a top-left isometric view of a male body of connector for fluid tubing.

FIG. 2 is a right side elevation view of the male body of FIG. 1.

FIG. 3 is a left side elevation view of the male body of FIG. 1.

FIG. 4 is a front elevation view of the male body of FIG. 1.

FIG. 5 is a rear elevation view of the male body of FIG. 1.

FIG. 6 is a top plan view of the male body of FIG. 1; and,

FIG. 7 is a bottom plan view of the male body of FIG. 1.

The broken lines shown in the drawings are for illustrative purposes only and form no part of the claimed design.
